GOLF BALL RETRIEVER

Ernest Lehman, 23490 Letchworth Road,
Cleveland, Ohio

Filed Oct. 22, 1965, Ser. No. 87,798

Term of patent 14 years

(Cl. D34—5)

FIG. 1

The broken line showing representing the drawing of a golf ball is for illustrative purposes only.

I claim:

The ornamental design for a golf ball retriever, as shown and described.
